(57) **CLAIM**

The ornamental design for a tracking device, as shown and described.

DESCRIPTION

The patent or application file contains at least one drawing executed in color. Copies of this patent or patent application publication with color drawing(s) will be provided by the Office upon request and payment of the necessary fee.

1. Tracking device

1.14 : Front

The top cover is covered with textile materials, plastic mesh or sheer fabric; figs. 1.8 and 1.9 show the state where the top cover is removed; fig. 1.10 shows the inside of the top cover; the right side view is omitted because it is a mirror image of the left side view; LEDs are arranged in an annular shape inside the 12 small circles shown in fig. 1.8 and fig. 1.9; the part where these LEDs are arranged is a push button, which can be pressed from the top of the top cover; the push buttons and LEDs are covered by the top cover, thus the LEDs are not visible from the top cover in figs. 1.1-1.3 when the LEDs are not lit; fig. 1.11 shows the state where 12 LEDs are lit in pink; fig. 1.12 shows the state where 12 LEDs are

(Continued)

lit in white; figs. 1.13 and 1.14 show aspects in which the number, position, order, and brightness of the LED lights are changed.
